UNITED STATES PATENT OFFICE.

WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY.

VALVE MECHANISM FOR ROCK DRILLS.

Application filed November 22, 1928. Serial No. 321,132.

This invention relates to rock drills, but more particularly to the valve mechanism intended for use in effecting the distribution of pressure fluid to the cylinder of 5 rock drills of the fluid actuated type.

The objects of the invention are to obtain a rapid action of the valve and to impart stability to the valve in its limiting positions, thus preventing leakage of pressure 10 fluid into the piston chamber in advance of the piston and a resulting loss in force of the blow of the hammer piston against the working implement which it is intended to actuate.

15 Other objects will be in part obvious and in part pointed out hereinafter.

In the drawings illustrating a practical application of the invention and in which similar reference characters refer to similar 20 parts,

Figure 1 is a vertical sectional elevation of a portion of the rock drill equipped with a valve mechanism constructed in accordance with the practice of the invention,

25 Figure 2 is a transverse view taken through Figure 1 on the line 2—2 looking in the direction indicated by the arrows, and

Figure 3 is a perspective view of the valve 30 and the parts comprising the valve chest.

Referring to the drawings, A designates a rock drill having a cylinder B in which is formed a piston chamber C to accommodate a reciprocating hammer piston D. The cylinder B has in this instance a free exhaust port E which is controlled by the piston D. Disposed at the forward end of the cylinder B is a front cylinder washer F which forms a closure for the front end of the piston 35 chamber C and has a bore G to slidably receive the nose or extension H of the piston D.

In the rearward end of the cylinder B is an enlarged bore J and in the innermost 45 end of said bore J is a back cylinder washer K which forms a closure for the rearward end of the piston chamber C.

The bore J may be of a suitable depth to receive, among other elements, rotation 50 mechanism comprising in this instance a rotation ratchet L which may be secured in operative position in any suitable manner. The rotation ratchet L has the usual intro-

verted teeth O adapted for engagement with spring pressed pawls P carried by the head Q of a rifle bar R for imparting rotary 55 movement to the piston D and thus also to the working implement which the piston is intended to actuate, the rifle bar R being of course interlocked slidably with the piston D in the usual manner.

In the construction illustrated, the rotation ratchet L serves as a seat for a back head S disposed at the extreme rearward end of the piston A and secured to the cylinder in any convenient manner, as for instance, by the usual side rods (not shown).

The back head S is provided with a throttle valve chamber T for the reception of a throttle valve U whereby the admission of pressure fluid from a source of supply into 70 the drill may be controlled. The throttle valve U as illustrated is of the rotary type and has a central chamber V which may be in constant communication with a source of pressure fluid supply. In the side wall of 75 the throttle valve is a port W which, in the open position of the throttle valve, registers with a passage X leading to a supply reservoir Y in the forward or inner end of the back head A.

Interposed between the back cylinder washer K and the rotation ratchet L is a valve mechanism designated generally by Z for effecting the distribution of pressure fluid to the ends of the piston chamber C to 85 actuate the piston. The valve mechanism in this instance comprises a valve chest b which serves as a seat for the rotation ratchet L and the head Q of the rifle bar and is in turn seated on a valve seat c disposed on the back cylinder washer K.

In the valve chest b is a valve chamber d from the forward side of which leads a rearward inlet passage e to the rearward end of the piston chamber C. From the same side 95 of the valve chamber d leads a front inlet passage f, that is, both the inlet passages e and f extend through the valve seat c and through the back cylinder washer K, and the inlet passage f is continued through the cylinder B to a point near the front end of the piston chamber C into which it opens.

The pressure fluid for actuating the piston D is conveyed to the valve chamber d through a plurality of supply passages g which lead 105

from the supply reservoir Y through the valve seat c where they open into cavities h in the forward surface of the valve seat so that the back cylinder washer K forms a closure for one side of said cavities. The pressure fluid admitted into the cavities h flows therefrom through ports j in the valve seat and which ports afford communication between the cavities h and the valve chamber d. The ports j in this instance open into the valve chamber d at points adjacent the inlet passages e and f and therefore lie directly beneath a distributing valve k disposed in the valve chamber d for controlling the distribution of pressure fluid to the piston chamber C.

The distributing valve k is illustrated as being of the oscillatory plate type having an intermediate fulcrum o upon which the valve 20 k is adapted to rock from one limiting position to the other, and has oppositely extending wings p and q which in this instance overlie both the supply ports j and the inlet passages e and f. If desired the valve chamber d may be provided at its rearward side 25 and at opposite ends with suitable recesses r into which pressure fluid may flow to act against the rearward surfaces of the wings p and q to assist in holding the seated ends 30 or wings of the valve firmly over the inlet passages which they control.

From the foregoing description, it will be readily apparent to those skilled in the art 35 that the valve k will be exposed to a positive pressure, that is, to full line pressure for actuating it from one limiting position to the other. The valve is in no wise dependent upon any suction action of the pressure fluid during its passage into the piston chamber 40 for its movement. In fact the pressure fluid does not pass over any portion of the valve during its course from the supply passages to the inlet passages such as its edges, as is customary in valves of this type, but flows 45 across only the forward surfaces of the wings p and q.

The operation of the device is as follows: With the throttle valve U in the open position, pressure fluid will flow through the port 50 W and the passage X into the supply reservoir Y. From thence it flows through the supply passages g into the cavities h and through the supply ports j to act against the wings p and q.

With the piston occupying the rearward-most position in the piston chamber C, the forward portion of the piston chamber will be open to atmosphere through the exhaust port E, therefore the pressure fluid acting 60 against the wings q will raise said wing and pressure fluid will then flow from the supply ports j into the valve chamber d, across the forward surface of the wing q through the inlet passage e and into the rearward end of

the piston chamber C to impel the piston D forwardly.

It will thus be noted that the pressure fluid during its course through the valve chamber d exerts a positive pressure against the forward surface of the wing q for holding said wing in the raised position. Pressure fluid will, of course, act against a portion of the rearward surface of the wing q.

Due to the differential in area of the exposed surfaces of the wing q, however, the pressure fluid acting against the forward surface will predominate and the valve will therefore remain firmly in the raised position until the piston D uncovers the free exhaust port E. When the piston D reaches this point in its travel, there will be an abrupt drop in pressure fluid in the rearward end of the piston chamber C and the valve k will be immediately tilted to its other limiting position, both by the compression created in the front end of the piston chamber C and by the pressure fluid acting against the forward surface of the wing p.

The reversal of the valve in the manner described may take place at or slightly prior to the instant at which the piston D delivers its blow against the working implement. Pressure fluid will then flow from the valve chamber through the inlet passage f into the front end of the piston chamber C to return the piston D to its initial position. During the rearward travel of the piston, compression will of course be created in the rearward end of the piston chamber C and such compression will act through the inlet passage e against the forward surface of the wing q to assist the live pressure fluid in the supply ports j which acts against the forward surface of the wing q for again tilting the valve k to its other limiting position.

I claim:

1. In a fluid actuated rock drill, the combination of a cylinder and a piston, an exhaust port for the cylinder, a valve chest having a valve chamber, inlet passages leading from one side of the valve chamber to the ends of the cylinder, an oscillatory plate valve in the valve chamber controlling the inlet passages, said valve having oppositely extending wings and an intermediate fulcrum whereon said valve is adapted to rock, and supply passages opening into the same side of the valve chamber as the inlet passages to expose the valve to pressure fluid for actuating said valve from one limiting position to another.

2. In a fluid actuated rock drill, the combination of a cylinder and a piston, an exhaust port for the cylinder, a valve chest having a valve chamber, inlet passages leading from one side of the valve chamber to the ends of the cylinder, an oscillatory plate valve in the valve chamber controlling the

- inlet passages, said valve having oppositely extending wings and an intermediate fulcrum whereon said valve is adapted to rock, and supply passages opening into the same 5 side of the valve chamber as the inlet passages to constantly expose the corresponding sides of the wings to pressure fluid under full line pressure for actuating said valve from one limiting position to another.
- 10 3. In a fluid actuated rock drill, the combination of a cylinder and a piston, an exhaust port for the cylinder, a valve chest having a valve chamber, inlet passages leading from the forward side of the valve chamber to the ends of the cylinder, an oscillatory plate valve in the valve chamber controlling the inlet passages, said valve having a pair of oppositely extending wings and an intermediate fulcrum whereon said valve is 15 adapted to rock, and supply passages opening into the forward side of the valve chamber to constantly expose the forward sur-
- faces of both wings to pressure fluid for actuating the valve from one limiting position to another. 25
4. In a fluid actuated rock drill, the combination of a cylinder and a piston, an exhaust port for the cylinder controlled by the piston, a valve chest having a valve chamber, inlet passages leading from the valve chamber to the cylinder, an oscillatory plate valve in the valve chamber having an intermediate fulcrum whereon said valve is adapted to rock and a pair of oppositely extending wings to control the inlet passages, and supply passages conveying pressure fluid into the valve chamber to expose corresponding surfaces of both wings to pressure fluid for actuating the valve and for supplying pressure fluid across one side of the valve to the 30 35 inlet passages. 40

In testimony whereof I have signed this specification.

WILLIAM A. SMITH, JR.
